BOOT STRETCHER

Earl R. Hawkins, Olathe, Kans., assignor to C. H. Hyer & Sons, Olathe, Kans., a corporation of Kansas

Application April 24, 1950, Serial No. 157,684

7 Claims. (Cl. 12—129.4)

1

This invention relates to boot stretchers commonly used to enlarge portions of a shoe or boot to relieve tightness or binding on the wearer's foot and especially to stretchers for that portion of the boot which is normally over the instep of the foot.

The primary object of this invention is to provide a boot stretcher having a pair of sections, one of the sections being placed on the sole of the boot and the other section being forcefully brought into stretching relationship with the boot.

Another important object of this invention is to provide a boot stretcher which may be introduced into the boot and apply a stretching force thereto at different locations within the boot, thereby adjusting the size of the boot as required to fit the foot on which the boot is to be worn.

A further object of this invention is to provide a boot stretcher having a pair of sections with a lever engaging both sections and a screw producing a lifting force on one section and bearing on one end of the lever, thereby raising the one section into engagement with the boot along a substantially rectilinear path.

Other objects of this invention include the way in which one section of the boot stretcher has a lever-receiving slot to facilitate insertion of the stretcher into the foot portion of the boot and a roller is located on the end of the lever which forcefully engages the one section, thereby reducing friction and the effort required to produce the desired stretching effect.

In the drawing,

Fig. 1 shows the boot stretcher in place in stretching relationship with a boot.

Fig. 2 is a fragmentary cross section along the line II—II in Fig. 1, looking in the direction of the arrows.

Fig. 3 is a fragmentary cross section taken along the line III—III of Fig. 1, looking in the direction of the arrows.

Fig. 4 is a fragmentary cross section taken along the longitudinal center line of the boot stretcher; and,

Fig. 5 is a cross section taken along line V—V of Fig. 4, looking in the direction of the arrows.

A boot 10 as shown in Fig. 1 has a boot stretcher located in the foot portion thereof. A section 12 of the boot stretcher is in engagement with sole 14 of boot 10 and is shaped to complementarily engage the boot sole 14 along a portion thereof. A second section 16 is formed in a foot shape having the upper surface rounded for engage-

2

ment with boot 10 in the portion thereof normally over the instep of the wearer.

Section 16 has a pair of links 18 in opposed relationship affixed to the lower and rear portion thereof extending downwardly. The rearmost portion of section 12 is disposed between links 18 and is rotatably mounted therebetween by means of pin 20. An elongated slot 22 formed along the center line of section 12 receives a lever 24 for rotation about a fulcrum pin 26 located intermediate the ends of slot 22 and lever 24.

Lever 24 has a socket 27 formed in the uppermost surface and at one end thereof. A roller 28 is disposed for rotation in the bifurcated portion of the lever at the opposed end of the socket 27. A screw 30 having a T-handle 32 at the uppermost end thereof extends through a bore 34 in section 16 and is threadably engaged by a collar 36 having a pair of opposed trunnions 38 integral therewith and rotatably mounted in section 16.

The lowermost end of screw 30 engages socket 27 in lever 24. Section 16 has a plurality of holes 40 formed in the upper surface for engagement with the boot 10 and for holding the same from slipping along the surface of said section 16 by the trapping of air in the holes 40 and thereby presenting a gripping action on boot 10. Bearing plate 42 is disposed on the undersurface of section 16 along the path of travel of roller 28. The diameter of bore 34 is sufficiently large to accommodate the rocking motion of screw 30 as the end thereof follows the end of lever 24.

In use, screw 30 is retracted until the complementary faces of the section 12 and movable section 16 are together, and lever 24 is submerged in slot 22. With the parts of the boot stretcher so disposed, it may be inserted into the foot portion of the boot 10 and the lowermost surface of section 12 brought to rest on sole 14. Screw 30 is then rotated by turning handle 32, thereby bringing the lowermost end into engagement with socket 27 of lever 24.

Further downward travel of the screw 30 causes the end of the lever 24 proximal to socket 27 to engage the sole 12 of the boot 10 and, in cooperation with the screw 30, to provide a lifting force through collar 36 and trunnions 38 to section 16. Further, the operation of screw 30 causes lever 24 to rotate about fulcrum pin 26 which brings roller 28 into engagement with bearing plate 42 on the lowermost portion of section 16. Roller 28 moves along the bearing plate 42 as the section 16 is raised.

Further movement of screw 30 produces a lift-

ing force on section 16 by the action of the roller 28 and in cooperation with the rotation of the lever 24 about fulcrum 26. Section 16 is thereby moved vertically in a substantially rectilinear path by virtue of being raised at the rear end and the forward ends simultaneously. The forward-mounted end of section 16 thereupon engages the butt end and stretches the material thereof as required. The openings 40 prevent the boot 10 from slipping off the rounded portion of section 16 and thereby facilitate the stretching of a particular area.

The boot stretcher is shown in a rearmost position in the boot 10 in Fig. 1, but it may be moved forward and used in a variety of positions, thus being useful to stretch any portion of the boot 10 from the toe rearward to the upper portion. To remove the boot stretcher from the boot 10, the screw 30 is turned in the opposite direction for collapsing the structure, whereupon lever 28 returns to the slot 22 and the section 16 returns to closed proximity to the section 12.

While the boot stretcher has been designed particularly for boots, it is manifest that the broad principles hereof might well be used for shoes and other types of footwear and provides a simple device for easily accomplishing the stretching required. Accordingly, it is desired to be limited only by the spirit of this invention as defined by the scope of the appended claims.

Having thus described my invention, what I claim as new and desire to secure by Letters Patent is:

1. A boot stretcher comprising a body having a pair of articulated sections and adapted for insertion into a boot, one of the sections bearing against a portion of said boot when the stretcher is in an operative position within the boot; a lever pivotally mounted on said one section; a manually manipulable screw carried by the other section for engagement with the lever at one side of the pivot thereof, said other section being disposed for engagement by the lever at a point on the opposite side of said pivot to exert pressure upon the other section and thereby force the latter against another portion of the boot when the screw is manipulated to swing the lever in one direction; and an elongated, lever-receiving slot in said one section, said lever being swingable to and from a position disposed entirely within said slot.

2. A boot stretcher comprising a body having a pair of articulated sections and adapted for insertion into a boot, one of the sections bearing against a portion of said boot when the stretcher is in an operative position within the boot; a lever pivotally mounted on said one section; a manually manipulable screw carried by the other section for engagement with the lever at one side of the pivot thereof, said other section being disposed for engagement by the lever at a point on the opposite side of said pivot to exert pressure upon the other section and thereby force the latter against another portion of the boot when the screw is manipulated to swing the lever in one direction; an elongated, lever-receiving slot in said one section, said lever being swingable to and from a position disposed entirely within said slot; and a collar threaded internally to receive the screw and having a pair of trunnions in opposed relationship integral therewith, said trunnions being received for rotation by the other section.

3. A boot stretcher comprising a body having

a pair of articulated sections and adapted for insertion into a boot, one of the sections bearing against a portion of said boot when the stretcher is in an operative position within the boot; a lever pivotally mounted on said one section; a manually manipulable screw carried by the other section for engagement with the lever at one side of the pivot thereof, said other section being disposed for engagement by the lever at a point on the opposite side of said pivot to exert pressure upon the other section and thereby force the latter against another portion of the boot when the screw is manipulated to swing the lever in one direction; an elongated, lever-receiving slot in said one section, said lever being swingable to and from a position disposed entirely within said slot; a collar threaded internally to receive the screw and having a pair of trunnions in opposed relationship integral therewith, said trunnions being received for rotation by the other section; and a roller mounted on the lever for engagement with the other section as the lever is swung on said pivot.

4. A boot stretcher comprising a body having a pair of articulated sections and adapted for insertion into a boot, one of the sections bearing against a portion of said boot when the stretcher is in an operative position within the boot; a lever pivotally mounted on said one section; and a manually-manipulable screw carried by the other section for engagement with the lever at one side of the pivot thereof, said other section being disposed for engagement by the lever at a point on the opposite side of said pivot to exert pressure upon the other section and thereby force the latter against another portion of the boot when the screw is manipulated to swing the lever in one direction.

5. A boot stretcher comprising a body having a pair of articulated sections and adapted for insertion into a boot, one of the sections bearing against a portion of said boot when the stretcher is in an operative position within the boot; a lever pivotally mounted on said one section; and a manually-manipulable screw carried by the other section for engagement with the lever at one side of the pivot thereof, said other section being disposed for engagement by the lever at a point on the opposite side of said pivot to exert pressure upon the other section and thereby force the latter against another portion of the boot when the screw is manipulated to swing the lever in one direction; and a screw-threaded collar swingably carried in the other section for receiving the screw.

6. A boot stretcher comprising a body having a pair of articulated sections and adapted for insertion into a boot when the stretcher is in an operative position within the boot; a lever pivotally mounted on said one section; and a manually-manipulable screw carried by the other section for engagement with the lever at one side of the pivot thereof, said other section being disposed for engagement by the lever at a point on the opposite side of said pivot to exert pressure upon the other section and thereby force the latter against another portion of the boot when the screw is manipulated to swing the lever in one direction; and a roller mounted on the lever for engagement with the other section as the lever is swung on said pivot.

7. A boot stretcher comprising a body having a pair of articulated sections and adapted for insertion into a boot, one of the sections bearing against a portion of said boot when the

stretcher is in an operative position within the boot; a lever pivotally mounted on said one section; a manually-manipulable screw carried by the other section for engagement with the lever at one side of the pivot thereof, said other section being disposed for engagement by the lever at a point on the opposite side of said pivot to exert pressure upon the other section and thereby force the latter against another portion of the

boot when the screw is manipulated to swing the lever in one direction; a screw-threaded collar swingably carried in the other section for receiving the screw; and a roller mounted on the lever for engagement with the other section as the lever is swung on said pivot.
